UNITED STATES PATENT OFFICE.

WALTER E. HUENEFIELD, OF CINCINNATI, OHIO, ASSIGNOR TO THE HUENEFIELD COMPANY, OF CINCINNATI, OHIO.

HYDROCARBON-BURNER.

1,070,603.

Specification of Letters Patent. Patented Aug. 19, 1913.

Application filed September 6, 1912. Serial No. 718,935.

To all whom it may concern:

Be it known that I, WALTER E. HUENEFIELD, a citizen of the United States, residing at Cincinnati, in the county of Hamilton and State of Ohio, have invented certain new and useful Improvements in Hydrocarbon-Burners; and I do hereby declare the following to be a full, clear, and exact description of the invention, such as will enable others skilled in the art to which it appertains to make and use the same.

This invention relates to improvements in hydrocarbon burners and more particularly to such as are adaptable for use with stoves of the type commonly known as "oil stoves";—one object of the invention being to provide simple and efficient wick limiting means carried by the combustion chamber member of the device, which will also operate to transmit the weight of the combustion chamber member to the wick to force the latter down when the combustion chamber member is moved from its elevated to its normal position.

With this and other objects in view, the invention consists in certain novel features of construction and combinations of parts as hereinafter set forth and pointed out in the claims.

In the accompanying drawings, Figure 1 is a sectional view of the device, with the parts in their normal operative positions. Fig. 2 is a similar view showing the parts forming the combustion chamber in elevated position. Fig. 3 is a transverse sectional view, on the line $x-x$ of Fig. 1. Fig. 4 is a transverse sectional view, on the line $y-y$ of Fig. 2, and Fig. 5 is a detail view.

1—2 represent two concentric wick-tubes separated sufficiently to form a wick-chamber between them, the lower end of said wick-chamber being closed in any suitable manner. A nipple 3 is secured to the outer wick-tube 1 for attachment to a supply pipe and this nipple communicates with the lower portion of the wick-chamber. The upper end of the outer wick-tube is provided with an outwardly projecting annular flange 4 which is depressed somewhat, forming an annular rib 5 at the upper extremity of the tube 1. The inner wick-tube 2 is provided with a depressed inwardly projecting flange 6 (the inner edge of which may be bent downwardly as at 7), and an annular rib 8 is thus formed at the upper

extremity of said inner tube 2. A wick 9 is located within the wick-chamber between the tubes 1 and 2 and provided with a perforated metal wick holder 10. A hollow boss 11 is located on the outer tube 1 and communicates with the wick chamber and from this boss, a tube 12 projects in a diagonal direction,—said tube 12 and boss 11 constituting suitable bearings for a shaft 13 which carries a toothed wheel 14 located within the boss 11 and adapted to mesh with perforations of the wick-holder for raising the wick when the shaft 13 is turned. A suitable knob or wheel 15 is secured to the free end of the shaft 13 to facilitate the manual operation of the wick lowering and raising devices. By so forming the upper ends of the wick-tubes 1—2 as to provide annular ribs adjacent to the wick, any charred portions of the latter can be readily removed without becoming lodged in the immediate vicinity of the wick and thus the burner can be easily kept clean.

The annular flanges at the upper ends of the wick-tubes 1 and 2 constitute seats for the lower ends of spaced foraminated shells 16 and 17 which are suitably spaced apart to form a combustion chamber 18 between them. The shells 16 and 17 are surrounded by a casing 19 which is spaced from the outer shell 17 and is open at its upper end,—the lower end of said casing being provided with an inwardly projecting bottom flange 20 having a plurality of perforations 21. The upper end of the inner shell 16 may be provided with a fixed cap or head 22 having suitable perforations and the lower end of said inner shell may be provided with a perforated cap 23. The shells 16 and 17 and the casing 19 may be held in proper relation to each other by means of transverse rods 24 which pass through them.

A spider 25 comprising a plurality of radial arms, is fixed within the inner wick-tube 2 of the burner and constitutes a part of the raising and lowering and locking means for the foraminated shells and their surrounding casing. A cylindrical portion 26 depends from the inner shell 16 or more strictly speaking, from the lower cap 23 of said shell and enters the cylindrical space formed by the inner wick tube 2 and said cylindrical portion 26 serves to assist in guiding the shells and their surrounding casing in their vertical movements. The lower end

of the cylinder 26 is notched or recessed so as to form a plurality of depending legs 27, each having a beveled edge 28, and each leg 27 is notched at its lower end to form a seat 29 and a stop 30. One of the legs 27 is provided above its lower end with an elongated slot 31 so that this leg will be made approximately L-shaped or hook shaped.

When the shells forming the combustion chamber are in their normal operative positions, they will be supported upon the annular flanges at the upper ends of the wick-tubes 1 and 2 and the legs 27 will be disposed between the arms of the spider 25 but without actual contact with the latter. When the shells forming the combustion chamber shall have been thus disposed, said shells with the casing 19 and the depending cylinder 26 can be turned so that one of the arms of the spider will enter the elongated slot 31 in one of the legs 27 and the parts will then be locked against vertical movement. By making the slot 31 of appreciable length, the shells can be partially rotated back and forth until they shall have become accurately seated upon the annular flanges of the wick-tubes 1 and 2 and thus prevent any detrimental air currents entering in close proximity to the upper end of the wick. The casing 19 is provided with a suitable knob or handle 32 for manipulating said casing and the shells 16-17 for raising the same above the wick, or for lowering them as will now be explained.

Assuming that the shells 16 and 17 are resting upon their seats on the wick-tubes 1 and 2 and it is desired to raise said shells, the operator will turn said shells and casing and the beveled edges 28 of the legs 27, riding on the arms of the spider 25, will cause said shells and casing to rise and when the seats 29 shall have become disposed upon the upper edges of said arms of the spider, the shells and casing will be supported in their raised positions above the wick. The stops 30 at the lower ends of the legs 27 will engage the arms of the spider and prevent the combustion shells and casing from being turned too far. After the wick shall have been lighted, the operator will turn the combustion shells and casing in the reverse direction far enough to move the seats 29 off of the arms of the spider 25 and then the weight of the parts will be sufficient to cause the combustion shells to move downwardly upon their seats at the upper ends of the wick tubes and then by a further rotation of the combustion shells and casing, the depending cylinder will be partly rotated and its L-shaped leg will be caused to coöperate with one of the arms of the spider to lock said combustion shells and casing against upward movement.

In order to prevent the wick from being

raised too far within the combustion chamber, I provide within the latter, near its lower end, a plurality of spaced limiting devices 33. These limiting devices may conveniently consist of a number of narrow fingers or stops disposed transversely within the lower portion of the combustion chamber and said stops or fingers may project from either of the shells 16-17 and they may be sustained and secured in place by means of a ring 34 secured in any suitable manner to one or the other of said shells.

From this construction it will be observed that the limiting means for the wick are carried by the vertical movable combustion shells and are therefore movable away from and toward the wick, but that when the burner is in operation, these limiting devices may be disposed in more or less close proximity to the wick without detracting from the efficiency of the flame. Should it happen that the operator would raise the wick until the perforated holder thereof passes the toothed wheel of the wick raising devices so that the turning of the shaft 13 in the reverse direction would not effect the lowering of the wick, the weight of the combustion shells and the casing transmitted to the upper end of the wick through the medium of the spaced stops or limiting devices 33, will cause the wick to be pushed down far enough to insure the engagement of the wick raising toothed wheel with the perforated wick holder.

While I have shown and described means for raising, lowering, locking and propping the combustion chamber member of the device, I do not herein claim these devices specifically, the same constituting the subject matter of my copending application Serial No. 718,936.

Various changes might be made in the details of construction and the relative arrangement of the parts without departing from the spirit of my invention or limiting its scope, and hence I do not wish to restrict myself to the precise details herein set forth, except as particularly specified in the claims.

Having fully described my invention what I claim as new and desire to secure by Letters-Patent, is:

1. In a hydrocarbon burner, the combination with a wick tube member, a combustion chamber comprising concentric foraminated shells adapted to rest upon the wick tube member, and means for raising and lowering said combustion chamber member, of an annular series of fingers carried by the combustion chamber member and vertically movable with the same, said fingers disposed transversely in the lower portion of the combustion chamber across the path of the wick so as to constitute limiting means for the latter.

2. In a hydrocarbon burner, the combina-

tion with a wick tube member, a combustion chamber member comprising concentric foraminated shells forming a combustion chamber between them, and means for raising and lowering the combustion chamber member, of a ring secured to the lower portion of one of the foraminated shells so as to be vertically movable with the combustion chamber member, and said ring provided 10 with an annular series of projections disposed transversely in the lower portion of

the combustion chamber in the path of the wick so as to constitute limiting means for the latter.

In testimony whereof, I have signed this 15 specification in the presence of two subscribing witnesses.

WALTER E. HUENEFELD.
